UNITED STATES PATENT OFFICE.

FRIEDRICH RASCHIG, OF LUDWIGSHAFEN-ON-THE-RHINE, GERMANY.

PROCESS FOR THE MANUFACTURE OF ALKALI EARTH SALTS OF HYDROXYLAMIN DISULFONIC ACID.

1,010,177.

Specification of Letters Patent. Patented Nov. 28, 1911.

No Drawing.

Application filed May 21, 1909. Serial No. 497,465.

To all whom it may concern:

Be it known that I, FRIEDRICH RASCHIG, manufacturing chemist, a subject of the German Emperor, residing at Ludwigshafen-on-the-Rhine, Germany, have invented certain new and useful Improvements in Processes for the Manufacture of Alkali Earth Salts of Hydroxylamin Disulfonic Acid, of which the following is a specification.

It is known, that by the action of alkali-nitrite on alkali-bisulfite-hydroxylamin-disulfonic acid, alkali-salts may be produced, which will easily split up into hydroxylamin-sulfate and alkali-sulfate. It has been found, however, that the equation

which was believed to represent the chemical reaction for this process, is not correct, and that it is not possible to obtain a large yield of hydroxylamin by bringing nitrite and bisulfite together in the proportions indicated by this equation. For in reality no free alkali results from this reaction, as long as it takes place in the cold, instead of which the nascent alkali saturates a third of the bisulfite by forming monosulfite; the reaction taking place between nitrite and bisulfite in the cold may, however, be represented by the following equation also as regards quantities:

The reaction according to this equation implies, of course, the loss of a third of the bisulfite, and also a loss of hydroxylamin, inasmuch as the subsequent hydrolyzation by acidulation splits off sulfurous acid, which partly unites with already formed hydroxylamin to form worthless amino-sulfonic acid.

It has already been recognized, that the reaction may be caused to run as indicated by equation I, by subsequently adding just the necessary quantity of mineral acid (hydrochloric or sulfuric acid) for saturating the alkali, which is set free, so as to form

neutral chlorid or sulfate. It is therefore necessary, that the reagents should act upon each other in the proportions indicated by the equation:

in which case an alkali salt of hydroxylamin disulfonic acid is obtained in practically the calculated quantity.

As an alternative, the nascent alkali may be supersaturated with sulfurous acid, thereby obtaining the further advantage of obtaining just enough bisulfite to transform a second molecule of nitrite into sodium hydroxylamin-disulfonate. By this process the disulfo-salt is obtained free from any other salts, which is a great advantage for the manufacture of hydroxylamin-sulfate in a pure condition, which, of course, is the ultimate object.

The reaction takes place almost exactly (also as regards quantities) in the sense of the equation:

The manufacture of the alkali-salt of hydroxylamin-disulfonic acid according to equation (4) *per se*, has been suggested to some extent by the statements of Divers in the *Journal of the Chemical Society* 77/1900, page 681.

The sodium in the nitrite or in the bisulfite or in both may, of course, be replaced by potassium or other alkali metals, but it could not be expected that in lieu of the same the calcium salts of nitrous and sulfurous acid may be employed. Neutral calcium sulfite being insoluble, the interaction of calcium nitrite and calcium-sulfite must cause neutral calcium-sulfite to be separated out, while a portion of the calcium-nitrite remains in solution. If afterward a mineral acid is added or sulfurous acid is introduced, it was probable that the latter would act on the dissolved calcium-nitrite, rather than acting on the undissolved calcium-sulfite, that consequently free nitrous acid would be formed and soon decomposed. As a matter of fact, nothing of this occurs, on the contrary the separated calcium-sulfite

dissolves in the added hydrochloric or sulfuric acid, and the reaction with calcium-salts, as well as with stronium- and barium-salts runs as smoothly and quantitatively as 5 with alkali-salts. This possibility of replacing the alkali-salts with lime-salts is of great commercial importance, because calcium nitrite may be produced (by conducting the nitrous gases arising from air in the flame 10 of electric high-tension lamps over lime kept moist by running water) much more cheaply than sodium-nitrite, and calcium-bisulfite is the cheapest of all bisulfites, because it is produced, as usual in the manufacture 15 of cellulose, directly from sulfurous gases (obtained by roasting pyrites etc.), lime and water. Moreover, the manufacture of hydroxylamin from the calcium salts of hydroxylamin-disulfonic acid is 20 very easy, because by its hydrolysis insoluble calcium-sulfate is produced, which can be readily separated from the easily soluble hydroxylamin-sulfate.

Example I: To 100 liters of calcium-nitrite solution (ten fold normal=660 grams of $\text{Ca}(\text{NO}_2)_2$ per liter) are added 4000 liters of commercial calcium-bisulfite-solution ($\frac{1}{2}n=30.5$ grams of $\text{CaH}_2(\text{SO}_3)_2$ per liter). Neutral calcium sulfite separates out 25 and forms a milky liquid. 100 liters of 10 fold normal sulfuric acid is now caused to flow into the liquid, while stirring and keeping the temperature below 10°C . by external cooling. The calcium sulfite enters 30 into solution and is replaced by calcium-sulfate. This is separated from the liquid by 35 filtration, thereby obtaining a clear liquid

containing almost the calculated quantity of calcium hydroxylamin-disulfonate

which liquid may be split in the known manner by heating, into hydroxylamin-sulfate, calcium sulfate and sulfonic acid.

Example II: To 100 liters of calcium-nitrite solution are added 2000 liters of calcium bisulfite solution, the liquid is cooled from outside, and 64 kilos of sulfuric acid are admitted. The previously precipitated calcium-sulfite is thereby re-dissolved, and 45 the final result is a clear solution of almost the calculated quantity of the pure calcium-salt of hydroxylamin-disulfonic acid.

What I claim is:

The process for the manufacture of 55 alkali earth salts of hydroxylamin-disulfonic acid, which consists in causing a nitrite of an alkali earth, a bisulfite of an alkali earth, and sulfuric acid to act upon one another in the cold, in the proportions 60 indicated by the equation

nitrite and bisulfite being brought together 65 first and the sulfuric acid added afterward, substantially as described.

In testimony whereof I have hereunto set my hand in presence of two subscribing witnesses.

FRIEDRICH RASCHIG.

Witnesses:

ROBERT GERLACH,
A. T. MITTON.
